CLAIM

The ornamental design for a infant cover-up, as shown and described.

DESCRIPTION

FIG. 1 is a perspective view of the infant cover-up showing my new design;

FIG. 2 is a top plan view thereof;

FIG. 3 is a front elevational view thereof;

FIG. 4 is a right side elevational view, the left side being a mirror image thereof;

FIG. 5 is a rear elevational view of the infant cover-up arranged at the same angle as FIG. 1; and,

FIG. 6 is a bottom elevational view thereof.

The broken line showing in FIG. 1 is for illustrative purposes only and forms no part of the claimed design.
